(57) **CLAIM**

The ornamental design for a waterproof soundbar outdoor TV enclosure as shown and described.

DESCRIPTION

FIG. 1 is a front, top and right perspective view of a waterproof soundbar outdoor TV enclosure, showing my new design.

FIG. 2 is a rear, bottom and left perspective view thereof; FIG. 3 is a front elevation view thereof.

FIG. 4 is a rear elevation view thereof.

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a partial enlarged view of the area labeled 9 in FIG. 2.

The broken lines shown in the drawings are included for the purpose of illustrating portions of the waterproof soundbar outdoor TV enclosure that form no part of the claimed design.

1 Claim, 9 Drawing Sheets
